UNITED STATES PATENT OFFICE.

OSWALD SCHLAUPITZ, OF CANTON, OHIO, ASSIGNOR TO THE TIMKEN ROLLER BEARING COMPANY, OF CANTON, OHIO, A CORPORATION OF OHIO.

PUNCH PRESS.

Application filed March 16, 1927. Serial No. 175,833.

My invention relates to presses for punching openings in annular articles, such as the cages of conical roller bearings and the like. The invention has for its principal object a press which is simple and easy to operate, which will accurately punch the openings, in which the work can be easily and accurately placed in position and held and in which the punchings are automatically disposed of without interfering with the operation of the press. The invention consists principally in a punch press in which a circular series of punches are mounted around the periphery of an axially bored base on which is mounted a die block with an axial bore opening into the bore of said base, the punch operating means being mounted in a head secured to the ram of the press. The invention further consists in the punch press and in the parts and combinations of parts hereinafter described and claimed.

In the accompanying drawings, wherein like reference characters indicate like parts wherever they occur,

Fig. 1 is a vertical sectional view on the line 1—1 of Fig. 3.

Fig. 2 is a part elevation, part sectional view showing the mechanism in a position different from that shown in Fig. 1,

Fig. 3 is a horizontal sectional view on the line 3—3 of Fig. 2, looking downward,

Fig. 4 is a cross sectional view on the line 4—4 of Fig. 2, looking downward,

Fig. 5 is a bottom plan view of the punch operating head; and

Fig. 6 is a detail view showing a plate for centering work on the die, if a second series of holes are to be punched.

Mounted on the bolster 1 or bed of a punch press is a base plate 2 having a threaded central opening into which is screwed a hollow block 3. Said block 3 is provided with a plurality of slots 4 in each of which are disposed the parallel spaced arms 5 of a punch holder 6 that is secured to the block 3 as by screws 7. Pivotal mounted on a pin 8 in the lower ends of the arms of each punch holder 6 is a punch 9 whose upper end portion 10 is shaped to cooperate with one of the transverse openings 11 in a die 12 that is mounted on the upper end of said block 3. Mounted in the upper end of each punch holder 6 is a screw 13 that serves as an abutment for the punch therein.

Preferably the die 12 is provided with a removable cap portion 14 secured to the top thereof, as by screws 15. The die 12 has a depending tubular portion 16 fitting in the upper end of the bore of said block 3. The die 12 is hollow, and the depending tubular portion 16 thereof is interiorly threaded. Threaded into said tubular depending portion 16 of the die 12 is the threaded upper end of a tubular die securing member 17 that has an annular rib 18 thereon that engages the under side of said block 3. Thus by screwing the tubular die securing member 17 tightly into the depending portion 16 of the die, the die 12 is firmly positioned.

The transverse slots 11 of the die 12 are equal in number to the punches 9 and shaped to cooperate therewith to punch the proper sized openings in the work, which is shown in the drawings as a conical cage 19 for roller bearings. The die 12 and its cap 14 are conical to conform to the conical interior of the work 19 and the die is provided with circumferential shoulders 20 between the slots, which shoulders serve to properly position the cage and support it during the punching operation.

The punch operating mechanism is carried by a head 21 that is secured to the ram 22 of the press. Disposed at the center of said head 21 is a clamp 23 having a conical recess 24 adapted to receive the upper end of a cage 19 and hold it on the die 12. Said clamp 23 has a shank portion 25 extending into a bore 26 provided therefor in the head 21. Said shank 25 has a reduced portion 27 that extends through a bushing 28 mounted in said bore of said head. A spring 29 coiled around the reduced portion 27 of the shank of said clamp engages said bushing 28 and the end of the body portion 25 of said shank. A screw 30 in the end of the shank prevents the clamp from dropping out of the head.

Secured to the under surface of the head 21 as by screws 31 are strips 32 that have inclined inner end portions 33 adapted to engage the upper ends of the punches 9 as the head 21 moves down toward the punches, thus positioning the punches so that they may be actuated to punch the work. Preferably the screws 31 pass through slots 34 in said punch positioning strips 32 so that the positions of said strips may be adjusted.

Threaded into the head 21 with their inner ends projecting into the open interior of said head are screw threaded pins 35 adapted to engage the upper end portions 36 of the punches to force the punches to engage the work and punch openings therein. Preferably said actuating pins 35 are set at an angle and the cooperating portions 36 of the punches are correspondingly beveled. Said punch actuating pins 35 are held by lock nuts 37.

Secured to the ram 22 of the press and extending through enlarged openings 38 in the bolster 1 are rods 39 whose lower ends are secured to a plate 40 that is adapted to actuate knockout mechanism as hereinafter described. The block 3 is provided with a plurality of vertical bores 41, one disposed alongside of each punch 9. Mounted in each bore 41 is a knockout pin 42 that has a beveled upper end 43 adapted to cooperate with a beveled portion 44 of a punch 9 to strip said punch from the work and move it away from the die 12. The lower end 45 of each knockout pin 42 is threaded and mounted in a threaded opening in an end flange 46 on a tubular member 47 that is slidable on the die securing tube 17. Nuts 48 on each pin 42 above and below said flange 46 hold the pin in position. The tubular member 47 that carries the knockout pins is provided with a bottom flange 49 to which are secured, at diametrically opposite points, as by nuts 50, rods 51 that extend downwardly. Each rod 51 is provided with projections 52 near the top and bottom. The rods 51 extend through a slot 53 in said knockout plate 40.

As the ram 22 of the press moves upward, the knockout plate 40 engages the upper projections 52 on said rods 51, thus raising the tubular carrier 47 and the knockout pins 42; and on the downward stroke of the ram, the knockout plate 40 engages the lower projections 52 on said rods, causing the knockout pins to be retracted, out of the way of the punches 9. The rods 51 have recessed lower ends. Mounted in the recess 54 of each rod is one furcation 55 of an operating handle 56 that is pivotally secured to a bracket 57 on the bolster as by a pin 58. The rods 51 are secured to the ends of the handle 56 by pins 59. Said carrier 47 and said knockout pins 42 may be manually actuated by means of the handle 56.

The operation of the punching press may be briefly described as follows:

With the ram 22 and head 21 clear of the die 12, the handle 56 is actuated, causing the knockout pins 42 to spread the punches 9 so that the conical blank 19 for a cage may be placed on the die. The ram 22 is then actuated and as it descends, the knockout plate 40 engages the lower projections 52 on the rods 51, withdrawing the knockout pins

42 (if they have not already been manually withdrawn by means of the handle). The clamp 23 engages the upper edge of the work 19 holding it on the die. The punch positioning strips 32 engage the upper edge portions of the punches 9 moving them slightly inward toward the work, in position to be engaged by the actuating pins 35. The punches are then engaged by the pins 35 and caused to punch out the work. The punchings from the work pass into the bore of the die 12 and drop down through the tubular die holder 17.

After the punching operation is completed, the ram 22 moves up again. The knockout plate 40 engages the upper projections 52 on the rods 51, raising the carrier 47 and knockout pins 42. The pins push the punches outward and then engage the lower edge of the cage 19, to strip it from the die.

The press shown in the drawings is adapted to punch seven equally spaced holes at one operation. If other holes are desired, a centering plate 60 may be secured to the die 12 between two of the openings 11 therein, as by a screw 61. One of the openings 62 of a partly punched cage may be placed over this centering plate and the operation repeated, to punch additional holes.

The above described punch press has numerous advantages: It is simple and easy to operate. The punches operate from the outside of the work and the work is firmly supported during the punching operation. The portions punched out of the work are disposed of without risk of interfering with the operation of the machine. Obviously numerous changes might be made without departing from the invention and I do not wish to be limited to the precise construction shown.

What I claim is:

1. A press comprising a bolster, a hollow block thereon, a hollow die on said block, the interior of said die communicating with the interior of said block, said die having transverse openings therethrough, a plurality of elongated punches disposed around the outer periphery of said block and pivotally supported at their lower ends, the upper end of each punch cooperating with a transverse hole of said die, the upper outer edge portions of said punches being beveled, a reciprocatable ram head and punch actuating means in said ram head, said means being angularly disposed to cooperate with the beveled portions of said punches.

2. A press comprising a bolster, a hollow block thereon, a hollow die at the top of said block, said die having transverse openings therethrough communicating with the interior thereof, punch supporting members secured around the periphery of said block, punches having their lower ends pivotally

- mounted in said supports and having their upper ends shaped to cooperate with the transverse holes of said die, a ram, a head secured to said ram, a spring pressed clamp in said head adapted to engage the upper edge of the work to hold it on the die, and punch actuating pins mounted in said head and adapted to force said punches inwardly toward the work.
- 10 3. A press comprising a bolster, a hollow block thereon, a hollow die at the top of said block, said die having transverse openings therethrough communicating with the interior thereof, punch supporting members secured around the periphery of said block, punches having their lower ends pivotally mounted in said supports and having their upper ends shaped to cooperate with the transverse holes of said die, abutment screws for said punches in the upper portions of said punch supporting members, a ram, a head secured to said ram, a spring pressed clamp in said head adapted to engage the upper edge of the work to hold it on the die, and punch actuating pins mounted in said head and adapted to force said punches inwardly toward the work.
- 15 4. A press comprising a bolster, a hollow block thereon, a hollow die at the top of said block, said die having transverse openings therethrough communicating with the interior thereof and having shouldered work supporting portions between said openings and below the level of the lower edges thereof, punch supporting members secured around the periphery of said block, punches having their lower ends pivotally mounted in said supports and having their upper ends shaped to cooperate with the transverse holes of said die, a ram, and a head secured to said ram, said head being provided with punch actuating means adapted to force said punches inwardly toward the work.
- 20 5. A press comprising a bolster, a hollow block thereon, a hollow die at the top of said block, said die having transverse openings therethrough communicating with the interior thereof and having shouldered work supporting portions between said openings and below the level of the lower edges thereof, punch supporting members secured around the periphery of said block, punches having their lower ends pivotally mounted in said supports and having their upper ends shaped to cooperate with the transverse holes of said die, a ram, a head secured to said ram, a spring pressed clamp in said head adapted to engage the upper edge of the work to hold it on the die, punch actuating pins mounted in said head and adapted to force said punches inwardly toward the work, knockout pins for swinging said punches clear of said die to permit work to be placed on said die and for stripping punched work from said die, means operatively connected with said ram for actuating said knockout pins and selectively operable manual means for actuating said knockout pins.
- 25 6. A press comprising a bolster, a hollow block thereon, a hollow die at the top of said block, said die having transverse openings therethrough communicating with the interior thereof, punch supporting members secured around the periphery of said block, punches having their lower ends pivotally mounted in said supports and having their upper ends shaped to cooperate with the transverse holes of said die, a ram, a head secured to said ram, punch actuating pins mounted in said head and adapted to force said punches inwardly toward the work, knockout pins for swinging said punches clear of said die to permit work to be placed on said die and for stripping punched work from said die, and means operatively connected with said ram for actuating said knockout pins.
- 30 7. A press comprising a bolster, a hollow block thereon, a hollow die at the top of said block, said die having transverse openings therethrough communicating with the interior thereof, punch supporting members secured around the periphery of said block, punches having their lower ends pivotally mounted in said supports and having their upper ends shaped to cooperate with the transverse holes of said die, a ram, a head secured to said ram, said head being provided with punch actuating means adapted to force said punches inwardly toward the work, knockout pins for swinging said punches clear of said die to permit work to be placed on said die and for stripping punched work from said die, means operatively connected with said ram for actuating said knockout pins and selectively operable manual means for actuating said knockout pins.
- 35 8. A press comprising a bolster, a hollow block thereon, a hollow die at the top of said block, said die having transverse openings therethrough communicating with the interior thereof, punch supporting members secured around the periphery of said block, punches having their lower ends pivotally mounted in said supports and having their upper ends shaped to cooperate with the transverse holes of said die, a ram, a head secured to said ram, a spring pressed clamp in said head adapted to engage the upper edge of the work to hold it on the die, punch actuating pins mounted in said head and adapted to force said punches inwardly toward the work, knockout pins for swinging said punches clear of said die and stripping work from said die, a carrier on which said knockout pins are fixed, rods extending from said carrier and having spaced projections thereon, a plate having a slot in which the portions of said rods between said projections are disposed and rods secured to said plate and said ram, whereby when said ram is moved away from said die, said plate engages one set of said projections to cause said knockout pins to operate and when

- said ram moves toward the die, said plate engages said other projections to cause said pins to be moved away from said punches and die.
9. A press comprising a bolster, a hollow block thereon, a hollow die at the top of said block, said die having transverse openings therethrough communicating with the interior thereof, punch supporting members secured around the periphery of said block, punches having their lower ends pivotally mounted in said supports and having their upper ends shaped to cooperate with the transverse holes of said die, a ram, a head secured to said ram, a spring pressed clamp in said head adapted to engage the upper edge of the work to hold it on the die, punch actuating pins mounted in said head and adapted to force said punches inwardly toward the work.
10. A punch press comprising a bolster, a hollow block thereon, a hollow die at the top of said block, said die having a tubular interiorly threaded portion disposed in the bore of said block, a tubular member having an annular shoulder abutting against the under side of said block and having a threaded upper end portion fitting in the tubular threaded portion of said die, said die having transverse openings therethrough communicating with the interior thereof, punch supporting members secured around the periphery of said block, punches having their lower ends pivotally mounted in said supports and having their upper ends shaped to cooperate with the transverse holes of said die, said block having a plurality of bores therethrough, one adjacent to each punch, a tubular carrier slidably mounted on the lower end of said tubular die securing member, said carrier having an upper flange to which are secured a plurality of knockout pins, each pin extending through one of said bores, said pins being adapted to swing punches away from the work and strip the work from the die, said carrier also having an annular bottom flange, rods projecting from said bottom flange and having spaced projections thereon, a knockout actuating plate having a slot whereby it is mounted on said rods between said projections, a ram, rods secured to the ends of said plate and to said ram, a head secured to said ram, a spring pressed clamp in said head adapted to engage the upper edge of the work to hold it on the die, punch positioning strips secured to the inner side of said head and punch actuating pins mounted in said head and adapted to force said punches inwardly toward the work.
11. A punch press comprising a bolster, a hollow block thereon, a hollow die at the top of said block, said die having a tubular interiorly threaded portion disposed in the bore of said block, a tubular member having an annular shoulder abutting against the under side of said block and having a threaded upper end portion fitting in the tubular threaded portion of said die, said die having transverse openings therethrough communicating with the interior thereof, punch supporting members secured around the periphery of said block, punches having their lower ends pivotally mounted in said supports and having their upper ends shaped to cooperate with the transverse holes of said die, said block having a plurality of bores therethrough, one adjacent to each punch, a tubular carrier slidably mounted on the lower end of said tubular die securing member, said carrier having an upper flange to which are secured a plurality of knockout pins, each pin extending through one of said bores, said pins being adapted to swing punches away from the work and strip the work from the die, said carrier also having an annular bottom flange, rods projecting from said bottom flange and having spaced projections thereon, a knockout actuating plate having a slot whereby it is mounted on said rods between said projections, a ram, rods secured to the ends of said plate and to said ram, a head secured to said ram, a spring pressed clamp in said head adapted to engage the upper edge of the work to hold it on the die, punch positioning strips secured to the inner side of said head and punch actuating pins mounted in said head and adapted to force said punches inwardly toward the work.
12. A punch press comprising a bolster, a hollow block thereon, a hollow die at the top of said block, a tubular member extending into said hollow block and having an annular shoulder abutting against the under side of said block, said die having transverse openings therethrough communicating with the interior thereof, punch supporting members secured around the periphery of said block, punches having their lower ends pivotally mounted in said supports and having their upper ends shaped to cooperate with the transverse holes of said die, said block having a plurality of bores therethrough, one adjacent to each punch, a tubular carrier slidably mounted on the lower end of said tubular die securing member, said carrier having an upper flange to which are secured a plurality of knockout pins, each pin extending through one of said bores, said pins being adapted to swing punches away from the work and strip the work from the die, said carrier also having an annular bottom flange, rods projecting from said bottom flange and having spaced projections thereon, a knockout actuating plate having a slot whereby it is mounted on said rods between said projections, a ram, rods secured to the ends of said plate and to said ram, a head secured to said ram, a spring pressed clamp in said head adapted to engage the upper edge of the work to hold it on the die, punch positioning strips secured to the inner side of said head and punch actuating pins mounted in said head and adapted to force said punches inwardly toward the work.

thereon, a knockout actuating plate having a slot whereby it is mounted on said rods between said projections, a ram, rods secured to the ends of said plate and to said ram, a head secured to said ram, a spring pressed clamp in said head adapted to engage the upper edge of the work to hold it on the die, and punch actuating pins mounted in said head and adapted to force said punches inwardly toward the work.
